UNITED STATES PATENT OFFICE.

WILLIAM M. BELT AND HERSCHEL C. SMITH, OF BLOOMINGTON, ILLINOIS, ASSIGNEES,
BY MESNE ASSIGNMENTS, TO AMERICAN CONCRETE FORMS COMPANY, OF BLOOM-
INGTON, ILLINOIS, A CORPORATION OF ILLINOIS.

CENTERING MEANS AND METHOD OF FORMING MONOLITHIC ARCHES.

1,350,772.

Specification of Letters Patent. Patented Aug. 24, 1920.

Application filed February 21, 1917. Serial No. 149,993.

To all whom it may concern:

Be it known that we, WILLIAM M. BELT and HERSCHEL C. SMITH, citizens of the United States, and residing at Bloomington, 5 in the county of McLean and State of Illinois, have invented certain new and useful Improvements in Centering Means and Methods of Forming Monolithic Arches, of which the following is a specification.

- 10 In a co-pending application, filed February 17, 1917, Serial No. 149,162, a mechanism and method has been disclosed for molding arch ribs to be used in combination with precast reinforced concrete slabs, to 15 build up a concrete arch. While the method disclosed in the co-pending application has many advantages, it may sometimes be desired where the essential advantages of the precast slab idea are not important, (as, for 20 instance, where there is no great hurry to put the bridge in use, or where the materials for concrete constructions are easily available, and do not have to be shipped long distances,) to make a monolithic construction. 25 To provide for this contingency, we have developed the invention herein disclosed, in which a mechanism, somewhat similar to that involved in the application referred to is employed but wherein by addition thereto it is possible to make the arch 30 monolithic.

In the drawings:

Figure 1 is an elevation of a portion of the rib centering frame.

35 Fig. 2 is a cross sectional view of a portion of an arch rib constructed according to our invention.

Fig. 3 is a sectional view of a modification of the invention.

40 The arch rib centering has side pieces 11 adjustably connected by links 12, to form a rib centering of any required span and rise, according to where the bolts 13 are set into the holes 14 in the reinforcing frames 45 15, as more fully described in the co-pending application. The side pieces 11 are bent over at their tops as indicated at 16, and are secured to the bottoms 17 for molding the bottoms of the arch ribs.

50 Instead of using reinforced concrete slabs resting upon the tops 16 of adjacent side pieces 11, and forming molds for the sides of the arch ribs, this invention contemplates the use of special centering 18 of

boards or the like, resting upon adjacent 55 tops 16 of the side pieces 11 of successive arch rib centerings and underlying blocks 19 to support the ends of the boards, thus forming a complete mold for the entire under surface of the arch, so that the concrete 60 may thereafter be poured not only for the rib portions of the arch, but for the entire barrel or body thereof. The board 18 may terminate substantially flush with the inner sides of the side pieces 11, but 65 preferably they project over to an extent sufficient to permit a firm support and the blocks 19 are used.

In Fig. 3 a modification of the invention is shown, wherein the inner surface of the 70 barrel of the arch is made perfectly smooth, as is sometimes desirable to avoid transverse obstructions, which catch rubbish, etc., in the event of floods. In this modification the center boards 18 are laid entirely across the 75 rib centering construction, or abutted at the center of the rib centering of the construction, blocks 19' being used, which completely fill up the top portion of the rib centering, each of which is attached to an 80 end of the two abutting boards. In this construction, the entire inside of the barrel of the arch is sheathed with boards so that a perfectly smooth surface is produced.

After the arch has been constructed and 85 the centering frames removed, the boards 18 are removed, leaving a solid monolithic arch.

In the event that it is not desired to have the ribs project below the under surface of 90 the arch, the boards may be laid all the way across the rib centerings as indicated in Fig. 3.

Having now described our invention, we 95 claim:

1. In a monolithic concrete arch construction in combination a plurality of narrow rib forming centering frames adjustable for rise and span, and easily removable temporary centering elements spanning adjacent rib-forming centering frames to form molds for the barrel of the arch between said rib centerings.

2. In monolithic concrete arch construction in combination a plurality of spaced adjustable narrow centering frames having means to form the rib only, and a plurality of centering elements spanning adjacent rib

centering frames to form molds for the under surface of the barrel of the arch.

3. In monolithic concrete arch construction in combination a plurality of spaced adjustable arch rib centerings having side portions to mold the sides of the portion of the ribs projecting below the barrel of the arch, and removable temporary supports resting at either end upon the adjacent vertical sides of successive rib centerings, whereby to form a mold for the bottom of the barrel of the arch.

4. In monolithic concrete arch construction in combination a plurality of arch rib centerings each comprising a series of connected mold sections having means to form a mold for the rib only, said connected mold sections having means for adjusting the rise and span of the rib centerings respectively and removable temporary supports resting at either end upon the adjacent sides of the rib centerings whereby to form a mold for the bottom of the barrel of the arch.

5. The method of forming a monolithic concrete arch which consists in setting up adjustable spaced arch rib-forming centering frames, adjusting said frames to give the desired span and rise, laying boards or

the like between and upon adjacent rib centerings to form a mold for the barrel of the arch, pouring concrete upon the top of the completed mold thus formed, allowing the concrete to harden, and subsequently removing the rib centerings and boards or the like, substantially as described.

35
6. In a monolithic concrete arch construction in combination, a plurality of spaced apart centering frames adjustable for rise and span and each having upwardly projecting side edges and a depressed bottom 40 to provide a rib forming mold, and removable mold boards spanning the space between said spaced apart frames, said boards resting with their ends on said side edges whereby when concrete is poured thereon, 45 the boards will form the barrel of the arch and the frames will form projecting ribs.

In witness whereof, we hereunto subscribe our names to this specification in the presence of two witnesses.

WILLIAM M. BELT.
HERSCHEL C. SMITH.
